ABSTRACT

Compounds of the formula

wherein

R is 1-tetrahydronaphthyl, 1-indanyl,
1- α -naphthylethyl, 1-(2-pyridyl)-ethyl,
1-phenyl-2,2,2-trifluoroethyl, 1-cyanobenzyl,
1-(2-phenyl)-phenylethyl, or
1-(N-methyl-3-indolyl)-ethyl;

R' is hydrogen; or

R and R' jointly with the connecting nitrogen atom
are 2-methylindolyl; and

R'' is isobutyl, neopentyl, or i-propoxy,
and their salts with physiologically tolerated bases
lower the blood sugar level in diabetes mellitus.

13 Claims, No Drawings

CERTAIN
4-(N-PYRIDIMIN-2-YLSULFAMOYL)-
PHENYLACETAMIDES

This application is a continuation in part of our co-pending application Ser. No. 129,948 filed Mar. 31, 1971 now abandoned.

In the parent application Ser. No. 129,948, there were disclosed compounds of the formula

wherein:

C^* is an axymmetric carbon atom,

A is a monocyclic aromatic ring which may contain two substituents R_1 and R_2 ,

X and Y are equal or different and each constitute a direct bond or methylene,

R_3 and R_4 are different and are hydrogen, straight-chained or branched alkyl having up to 4 carbon atoms, carboxyl or alkoxy carbonyl having up to 4 carbon atoms in the alkoxy group,

R_5 and R_7 are equal or different and are hydrogen or alkyl having up to 4 carbon atoms,

R_6 is straight chained or branched alkyl having up to 6 carbon atoms, and

W is a direct C-C bond, oxygen, or sulfur, and their salts with physiologically tolerated bases.

These compounds are suitable for treatment of diabetes mellitus.

It has now been found that a strong lowering effect on the blood sugar level is also produced by sulfamoylpyrimidines of the formula

wherein

R is 1-tetrahydronaphthyl, 1-indanyl, 1- α -naphthylethyl, 1-(2-pyridyl)-ethyl, 1-phenyl-2,2,2-trifluoroethyl, 1-cyanobenzyl, 1-(2-phenyl)-phenylethyl, or 1-(N-methyl-3-indolyl)-ethyl;

R' is hydrogen; or

R and R' jointly with the connecting nitrogen atom are 2-methylindoyl; and

R'' is isobutyl neopentyl or i-propoxy,

and salts of said sulfamoylpyrimidines with physiologically tolerated bases.

The tests for blood sugar level is performed hourly for six hours on a rabbit having fasted for 24 hours. The lowest dosage, for example of 4-[N-(5-isobutyl-2-pyrimidinyl)-sulfamoyl]-phenylacetic acid 1- α -naphthylethylamide which lowers the blood sugar level as strongly as 1 mg/kg 4-[N-(5-isopropoxy-2-pyrimidinyl)-sulfamoyl]-phenylacetic acid 5-chloro-2-methoxyanilide, one of the most effective compounds disclosed in Belgian Patent No. 726,253, is near 3 for the (+) form, and near 0.1 for the (-) form (tested dosage levels being: 30, 3, 1, 0.5, 0.25, 0.1, 0.05 mg/kg).

It is surprising that the increase in the blood sugar level lowering effect is brought about by a change of the molecule in the extended side chain of the sulfonated benzene nucleus, that is, in a location which does not necessarily relate to the β -zytotropic effect of the sulfonamides, since even compounds having no side chains, such as Glymidin, have β -zytotropic effect.

For their therapeutic use, the compounds of the in-

vention may be administered orally as the free sulfonamides, as salts with physiologically tolerated inorganic and/or organic bases, such as sodium, lithium, calcium, ammonium hydroxides, amines such as methylglucamine, morpholine, ethanolamine, and the like, also in the form of mixtures of the free sulfonamides with a suitable alkali metal carbonate or bicarbonate. Bases which themselves lower the blood sugar level, such as

15 butyl biguanide, are particularly suitable. The novel compounds may be compounded with or without the additives usual in galenic pharmacy, carriers, taste improving agents, and the like, to form, for example, powders, as tablets, dragees, capsules, pills, in the form of suspensions or solutions.

The novel compounds of the above formula are prepared in the manner disclosed in the parent application as further illustrated in the following Examples.

EXAMPLE 1

4-[N-(5-Isobutyl-2-pyrimidinyl)-sulfamoyl]-phenylacetic acid

1-tetrahydronaphthylamide

30 A solution of 22 millimole (mM) triethylamine and 22 mM 1-aminotetrahydronaphthalene in 30 ml acetone was added dropwise to a solution of 20 mM 4-[N-(5-isobutyl-2-pyrimidinyl)-sulfamoyl]-phenylacetyl chloride in 70 ml acetone. The mixture was held for 16 hours at 20° C, then heated to a boil for 90 minutes, cooled, and filtered with suction. The recovered solid was recrystallized from ethanol.

Yield: 4.5 g of melting point 174° C.

EXAMPLE 2

4-[N-(5-Isobutyl-2-pyrimidinyl)-sulfamoyl]-phenylacetic acid

1-indanyl amide

45 The compound was prepared in a manner analogous to Example 1 from 1-aminoindane. Yield: 5.8 g of melting point 154° C.

EXAMPLE 3

R(+)-4-[N-(5-Isobutyl-2-pyrimidinyl)-sulfamoyl]-phenylacetic acid

1- α -naphthylethylamide

55 The compound was prepared as in Example 1 using R(+)-1- α -naphthylethylamine, and recrystallized from acetone-water mixture 1:1.

Yield: 3.7 g of melting point 172° C. $[\alpha]D^{20} = +27^\circ$

(c=1, chloroform).

EXAMPLE 4

S(-)-4-[N-(5-Isobutyl-2-pyrimidinyl)-sulfamoyl]-phenylacetic acid

1- α -naphthylethylamide

65 The compound was prepared as in Example 1 from S(-)-1- α -naphthylethylamine, and recrystallized from acetone/water mixture 1:1.

Yield: 4.0 g of melting point 172° C. $[\alpha]D^{20} = -23.7^\circ$ (c=1, chloroform).

EXAMPLE 5

S(-)-4-[N-(5-Neopentyl-2-pyrimidinyl)-sulfamoyl]-phenylacetic acid
1- α -naphthylethylamide

2-Amino-5-neopentylpyrimidine was prepared by a procedure generally known for synthesizing 2-amino-5-alkylpyrimidines (Arzneimittelforschung 14 [1964] J373).

56 Millimoles of the prepared compound were treated with 4-chlorosulfonyl-phenylacetic acid in 100 ml pyridin for 2 hours at 80° C. Aqueous hydrochloric acid was added to form a precipitate in which the dimethylamide moiety was saponified by means of 3% sodium hydroxide solution in 6 hours at a boil. The saponification mixture was filtered hot, and 4-[N-(5-neopentyl-2-pyrimidinyl)-sulfamoyl]-phenylacetic acid was precipitated with hydrochloric acid from the filtrate and recrystallized from methylglycol/ethanol mixture. It weighed 14.2 g and melted at 250° C. The acid was converted to the acyl chloride with thionyl chloride, and 19 mM of the acyl chloride were reacted with 28 mM (S)-1- α -naphthylethylamine and 20 mM triethylamine in 100 ml chloroform at boiling heat in 1 hour. The solvent was evaporated, the residue was suspended in dilute hydrochloric acid, and sequentially recrystallized from pyridine-water mixture and isopropanol-acetone-water.

The desired product was ultimately obtained in a yield of 46% and melted at 166° C. $[\alpha]D^{20} = -25^\circ$ (c=1, chloroform).

EXAMPLE 6

S(-)-4-[N-(5-Isopropoxy-2-pyrimidinyl)-sulfamoyl]-phenylacetic acid 1- α -naphthylethylamide

The compound was prepared as in Example 1 using 4-[N-(5-isopropoxy-2-pyrimidinyl)-sulfamoyl]-phenylacetyl chloride and (S)-1- α -naphthylethylamine. Yield: 43% of theory. Melting point: 183° C.

EXAMPLE 7

4-[N-(5-Isobutyl-2-pyrimidinyl)-sulfamoyl]-phenylacetic acid+1-(2-pyridyl)-ethylamide

The compound was prepared by analogy with Example 1 from 1-(2-pyridyl)-ethylamine. However, the acetone was distilled off, the residue was suspended in dilute hydrochloric acid and extracted with chloroform. The residue obtained after evaporation of the chloroform was taken up in aqueous sodium bicarbonate solution, the mixture was filtered, the filtrate was acidified, and the precipitate formed thereby was filtered off with suction and taken up in aqueous ammonia. The solution was filtered over charcoal and acidified to pH 6 with 20% acetic acid. The precipitate was recrystallized from ethanol-water.

Yield: 1.2 g containing 1.4% water. Melting point: 84° C.

EXAMPLE 8

4-[N-(5-Isobutyl-2-pyrimidinyl)-sulfamoyl]-phenylacetic acid
1-phenyl-2,2,2-trifluoroethylamide

5 The compound was prepared by analogy with Example 1 using 1-phenyl-2,2,2-trifluoroethylamine. Yield: 30% of theory. melting point: 168° C.

EXAMPLE 9

4-[N-(5-Isobutyl-2-pyrimidinyl)-sulfamoyl]-phenylacetic acid
1-cyanobenzylamide

15 The compound was prepared from 2-phenylglycine nitrile by analogy with Example 1. Yield: 13% of theory. Melting Point: 140° C.

EXAMPLE 10

4-[N-(5-Isobutyl-2-pyrimidinyl)-sulfamoyl]-phenylacetic acid
1-(2-phenyl)-phenylethylamide

25 The compound was prepared by the method of Example 1 from 1-(2-biphenyl)-ethylamine which had been obtained from 2'-phenylacetophenone by reducing amination with ammonium formate according to Wallach-Leuckert. Yield: 23% of theory. Melting point: 98° C.

EXAMPLE 11

4-[N-(5-Neopentyl-2-pyrimidinyl)-sulfamoyl]-phenylacetic acid
1-(N-methyl-3-indolyl)-ethylamide

35 The compound was prepared according to Example 1 from 1-(1-methyl-3-indolyl)-ethylamine.

EXAMPLE 12

4-[N-(5-Isobutyl-2-pyrimidinyl)-sulfamoyl]-phenylacetic acid
2'-methylindolinide

The compound was prepared according to Example 1 from 2-methylindoline. Yield: 40% of theory. Melting point: 171° C (hydrate).

We claim:

1. A compound which is a sulfamoylpyrimidine of the formula

55 wherein

R is 1-tetrahydronaphthyl, 1-indanyl, 1- α -naphthylethyl, 1-(2-pyridyl)-ethyl, 1-phenyl-2,2,2-trifluoroethyl, 1-cyanobenzyl, 1-(2-phenyl)-phenylethyl, or 1-(N-methyl-3-indolyl)-ethyl;

60 R' is hydrogen, or R and R' jointly with the connecting nitrogen atom are 2-methylindolyl; and

R'' is isobutyl, neopentyl, or isopropoxy; or a salt of said sulfamoylpyrimidine with a physiologically tolerated base.

65 2. A compound as set forth in claim 1, wherein said sulfamoylpyrimidine is 4-[N-(5-Isobutyl-2-

pyrimidinyl)-sulfamoyl]-phenylacetic acid-1-tetrahydronaphthylamide.

3. A compound as set forth in claim 1, wherein said sulfamoylpyrimidine is 4-[N-(5-Isobutyl-2-pyrimidinyl)-sulfamoyl]-phenylacetic acid 1-indanylamide.

4. A compound as set forth in claim 1, wherein said sulfamoylpyrimidine is R(+)-4-[N-(5-Isobutyl-2-pyrimidinyl)-sulfamoyl]-phenylacetic acid-1- α -naphthylethylamide.

5. A compound as set forth in claim 1, wherein said sulfamoylpyrimidine is S(-)-4-[N-(5-Isobutyl-2-pyrimidinyl)-sulfamoyl]-phenylacetic acid-1- α -naphthylethylamide.

6. A compound as set forth in claim 1, wherein said sulfamoylpyrimidine is S(-)-4-[N-(5-Neopentyl-2-pyrimidinyl)-sulfamoyl]-phenylacetic acid-1- α -naphthylethylamide.

7. A compound as set forth in claim 1, wherein said sulfamoylpyrimidine is S(-)-4-[N-(5-Isopropoxy-2-pyrimidinyl)-sulfamoyl]-phenylacetic acid-1- α -naphthylethylamide.

8. A compound as set forth in claim 1, wherein said sulfamoylpyrimidine is 4-[N-(5-Isobutyl-2-

pyrimidinyl)-sulfamoyl]-phenylacetic acid-1-(2-pyridyl)-ethylamide.

9. A compound as set forth in claim 1, wherein said sulfamoylpyrimidine is 4-[N-(5-Isobutyl-2-pyrimidinyl)-sulfamoyl]-phenylacetic acid-1-phenyl-2,2,2-trifluoroethylamide.

10. A compound as set forth in claim 1, wherein said sulfamoylpyrimidine is 4-[N-(5-Isobutyl-2-pyrimidinyl)-sulfamoyl]-phenylacetic acid-1-cyano-benzylamide.

11. A compound as set forth in claim 1, wherein said sulfamoylpyrimidine is 4-[N-(5-Isobutyl-2-pyrimidinyl)-sulfamoyl]-phenylacetic acid 1-(2-phenyl)-phenylethylamide.

12. A compound as set forth in claim 1, wherein said sulfamoylpyrimidine is 4-[N-(5-Neopentyl-2-pyrimidinyl)-sulfamoyl]-phenylacetic acid 1-(N-methyl-3-indolyl)-ethylamide.

13. A compound as set forth in claim 1, wherein said sulfamoylpyrimidine is 4-[N-(5-Isobutyl-2-pyrimidinyl)-sulfamoyl]-phenylacetic acid 2'-methylindolinide.
